Primary Examiner — Prabhakar Deshmukh(74) *Attorney, Agent, or Firm* — Banner & Witcoff, Ltd.(57) **CLAIM**

The ornamental design for a handleset, as shown and described.

DESCRIPTION

FIG. 1 is a front perspective view of a handleset showing my new design;

FIG. 2 is a front view thereof;

FIG. 3 is a rear view thereof

FIG. 4 is a left side view thereof;

FIG. 5 is a right side view thereof;

FIG. 6 is a top view thereof; and,

FIG. 7 is a bottom view thereof.

The broken line showing of the circular lock region and keyway and of the rear surface of the handleset represents unclaimed subject matter and forms no part of the claimed design.
